CLAIM

(72) Inventors: **Joshua D. Howard**, Osprey, FL (US); **Lydia F. Howard**, Osprey, FL (US); **Samuel Howard**, Osprey, FL (US)

The ornamental design for a holder for bag such as pet waste bag, as shown and described.

(73) Assignee: **HOWARD INNOVATIONS, LLC**, Osprey, FL (US)

DESCRIPTION

(**) Term: **15 Years**

(21) Appl. No.: **29/701,268**

(22) Filed: **Aug. 9, 2019**

FIG. 1 is a front perspective view of a holder for bag such as pet waste bag showing our new design according to a first embodiment;

(51) LOC (12) Cl. **03-01**

FIG. 2 is a front view of the first embodiment;

(52) U.S. Cl.

FIG. 3 is a rear view of the first embodiment;

USPC **D3/328**

FIG. 4 is a right side view of the first embodiment;

(58) **Field of Classification Search**

FIG. 5 is a left side view of the first embodiment;

USPC **D3/328; D8/367**
CPC .. A45C 3/04; A45C 13/00; A45C 5/14; A45C
11/00

FIG. 6 is a top view of the first embodiment;

See application file for complete search history.

FIG. 7 is a bottom view of the first embodiment;

(56) **References Cited**

FIG. 8 is rear perspective view of the first embodiment; and,

U.S. PATENT DOCUMENTS

FIG. 9 is a front view of a holder for bag such as pet waste bag showing our new design according to a second embodiment, the second embodiment being identical to the first embodiment except that the second embodiment has one indeterminate length as indicated in FIG. 9.

D447,947 S *	9/2001	Nakagawa	D3/328
D476,815 S *	7/2003	Richter	D3/328
D653,525 S *	2/2012	Pottes	D8/367
D713,149 S *	9/2014	Swisa	D3/328
D756,657 S *	5/2016	Fisher	D3/328
D763,065 S *	8/2016	Tu	D8/367
D764,803 S *	8/2016	Chiou	D3/328
9,625,088 B1 *	4/2017	Tan	A63B 55/408
D849,518 S *	5/2019	Crawford	D8/367

In FIG. 9, the second embodiment of the holder for bag such as pet waste bag is shown with break lines to indicate the one indeterminate length in FIG. 9; the appearance of any portion of the second embodiment of the holder for bag such as pet waste bag between the break lines forms no part of the claimed design.

The broken lines in FIGS. 1-5 and 7-9 show portions of the holder for bag such as pet waste bag that form no part of the claimed design.
